GRINDER

Charles D. Ammon, Lincoln, Nebr.

Application October 14, 1935, Serial No. 44,853

5 Claims. (Cl. 83—11)

My invention relates to mills and especially to the mills of the type known as hammer mills in which the hammers are rotated at high velocities about an axis to crush the material partly by the impact of the hammers against the material and partly by the impact of the material as it is forcibly hurled against stationary anvils.

The primary object of the invention is the provision of a mill which will not clog, particularly when the velocity of the hammers slows up.

Another object of the invention is the provision of a rearrangement of the parts of a hammer mill for lifting the ground material with a greatly reduced expenditure of energy whereby the ground material may be handled in the mill at much lower velocities.

Another object of the invention is the provision of a baffle which may be adjusted relative to the mouth of the mill for reducing the tendency of the mill to choke at that point and resulting in a more uniform feeding of the material into the mill.

Another object of the invention is the provision of an improved device for facilitating the insertion and removal of screens to make it possible to insert or to remove the screens much more quickly and easily than has heretofore been possible.

Still another object of the invention is the provision of a novel form of screen clamp which not only provides means for applying powerful pressure to seat the screen in place but which applies opposing tangential thrusts against the opposite edges of the screen to buckle the screen into its normal position against abutments which prevent excessive buckling of the screen from the material in the grinder chamber of the mill.

Having in view these objects and others which will be pointed out in the following description, I will now refer to the drawings, in which

Figure 1 is a view in perspective of the entire mill, parts being broken away to disclose interior construction.

Figure 2 is a view in vertical section through the grinding chamber.

Figure 3 is a view in perspective of a detail for adjusting the anvil.

Figure 4 is a view in vertical transverse section of the mill showing particularly the grinder and fan chambers in their relation to each other and showing also the shaft which carries both the hammer reel and the fans.

Figure 5 is a sectional view of a fragment of the mill showing particularly the screen clamping mechanism.

The mill or grinding chamber includes a front wall 10, a top wall 11, a rear wall 12 and side walls 13 and 14. The rear wall 12 as well as the side walls 13 and 14 merge into a conduit 15 having a generally horizontal direction.

Secured to the mill or grinding chamber of the mill is a fan chamber 16 containing the fan 17. This fan is secured to a shaft which also carries the hammers 18 and which has its bearings in the side walls 13 and 14. The fan chamber 16 is provided with a top opening 19 through which the ground material is driven by the blast of air. The opening 19 is so arranged that a discharge pipe may be secured thereto for delivering the ground material at any desired point. The conduit 15 enters the fan chamber 16 through its outer side wall.

The screen 20 is positioned in the rear of the hammer reel 21 and forward of the rear wall 12 and centrally of or near the level of the hammer reel. This arrangement is important in reducing to a minimum the lift of the ground material to the blower unit, thus preventing the choking of the passageway when the fan is slowing down. The mill casing is provided with a door 22 for giving access to the screen 20. This screen abuts against the edge of the bottom wall of the grinder chamber under the anvil 23 which securely holds the lower portion of the screen in position. The closing of the door 22 maintains the screen in firm position but this screen may be readily removed and replaced whenever desired by first opening the door 22, this being subsequently described more fully. The hammer mill casing is also provided with a funnel inlet 24 in its forward wall 10.

The material entering through the funnel 24 is acted upon by the hammers 18 and the ground material is forced through the apertures of the screen 20. These hammers due to their rapid rotation develop great centrifugal force and set up a powerful current of air which forces the ground material against the screen but this action is intensified by the suction of the fan 17 which causes a partial vacuum in the rear of the screen 20. The material thus ground is discharged through the opening 19. The ground material must pass through the conduit 15 which is horizontally positioned so that it is not lifted in its passage from the screen 20 to the fan 17. This is of importance since the slowing down of the fan will otherwise result in the choking of the mill.

In Figures 2 and 3, I show additional mechanism for preventing the choking of the mill. The material is ground not only by the hammers

55

18 but it is hurled against a baffle 27 which further reduces the material. This baffle 27 lies approximately in the tangent of the circle of rotation of the hammers, the tangent passing through 5 the funnel 24. Stationary anvils similar to the baffle 27 are in common occurrence in hammer mills but a fixed position for the initial baffle is undesirable in mills which are designed for grinding feeds all the way from grains to damp hay. 10 When the baffle is in fixed position it may function perfectly for one kind of material but the mill may clog up when another kind of material is used due to the fact that the baffle is in the wrong position relative to the feed opening when 15 the mill is used for another kind of material. I therefore provide an adjustment of the baffle relative to the opening as shown in Figures 2 and 3.

Secured to the side wall 14 is an L-shaped bracket 28 which is arcuate and concentric with 20 the shaft of the mill. The side wall 14 of the mill is provided with an arcuate slot 29 immediately above the upper edge of the bracket 28, the slot 29 being adapted to receive the end of the baffle 27 as shown in Figure 3. This baffle 27 25 not only passes through the slot 29 but it is adjustable therein by movement back and forth in the slot 29. The thrust of the material against the anvil 27 is rearward. In the rear of the anvil and at the rear end of the bracket 28 is an 30 L-shaped bracket 30 having a screw threaded aperture for the reception of a set screw 31, the end of the set screw bearing against the rear edge of the anvil 27. The anvil 27 may thus be moved forwardly by means of the set screw 31. 35 If it is desired to move the anvil 27 rearwardly it is only necessary to turn the screw in the reverse direction so that the impact of the material against the forward edge of the baffle 27 will cause the baffle to move rearwardly until it contacts 40 with the end of the set screw 31.

As best shown in Figure 2, the screen 20 is in the rear end of the grinder chamber and the opening for the screen is relatively large. The lower and upper edges of the screen lie substantially in the projected lower and upper horizontal tangential planes of the cylinder of rotation of the hammers. The anvil 23 is positioned to overlie the lower edge of the screen opening so that the screen 20 may be inserted underneath 45 the anvil 23 to form a continuation of the lower wall of the grinder chamber. A screen holder frame consisting of two or more arcuate members is employed to bear against the rear surface of the screen 20 at its edges. These arcuate members are each preferably in the form of a plurality of sections 32 and 33 but their number may be either increased or decreased. The section 32 is secured to a rod 34 which may serve as a pivot if only one section is employed or if otherwise desired when more than one section is employed. The section 32 may also be an arcuate rib projecting inwardly from a side wall of the grinder chamber and integral therewith. The sections 32 and 33 are secured to the rod 35 which 55 functions as a pivot for the section 33. The arm 36 is eccentrically pivoted to the upper end of the section 33. On the under side of the arm 36 is a bar 37 which projects slightly beyond the edge of the arm 36. When the screen is secured in place 60 the arm 36 abuts squarely against the upper edge of the screen so that the thrust of the arm 36 on the screen 20 is tangential and toward its lower edge.

A bar 38 is secured to the top wall 11 of the 65 grinder chamber, the bar being underneath the

pivot of the door 22 and projecting slightly beyond the edge of the door. In the Figure 2 position the arm 36 has its forward edge abutting against the rear edge of the top wall 11.

The importance of this structure resides in the 5 ease with which screens may be withdrawn and replaced and still more in the fact that the screens are very firmly held in place without direct clamping action. The only clamping action is at the upper and lower edges of the arcuate screen 10 but even this is relatively light because the dependence is placed mainly on the tangential thrust against the screen at the upper and lower edges. The action of the material in the grinder chamber is such that the thrust against the screen 15 is tangential and in an upward direction.

The screen is in effect buckled into its normal shape by reason of the pressures exerted at the upper and lower edges of the screen. The arcuate members 32 and 33 serve merely to prevent 20 excessive buckling. When it is desired to remove a screen it is only necessary to first lift the lid 22 and then to grasp the arm 36 and to lift it on its pivot. The pivoted arcuate section may then be lifted to entirely free the screen so that 25 the screen may be lifted out. Another screen may then be inserted and the arcuate members may be swung forwardly on their pivots so that the screen may be clamped by pressing down on the arm 36. This engages the rear edge of the arm 30 36 with the top edge of the screen so that downward movement of the arm 36 will exert a powerful pressure to fully seat the lower edge of the screen. The closing of the door 22 will then still further depress the arm 36 and it will firmly retain the arm 36 in its closed position. The door 35 22 may be latched in closed position by means of any desirable latching mechanism such as the thumb nuts 39. The buckling of the screen against the arcuate ribs entirely eliminates the 40 vibration and chattering which is so troublesome in all other hammer mills and in fact in all other mills operating at high speeds.

In many of the prior mills the body of the mill is divided through the center, one part opening up to permit the removal of the screen. It is readily apparent, however, that this greatly weakens the structure of the mill. In other mills various doors are provided for giving access to the screen but none of these effectively seals the opening against the expulsion of ground feed around the door nor provides convenient means for locking the screens tightly in position.

Having thus described my invention in such full, clear, and exact terms that its construction 55 and operation will be readily understood by others skilled in the art to which it pertains, what I claim as new and desire to secure by Letters Patent of the United States is:

1. A hammer mill including a casing and a 60 hammer reel therein, a hinged door in the rear portion of the top wall of said casing, a grinder chamber surrounding said hammer reel and having a floor in the form of a cylindrical arc, an arcuate screen abutting at its lower edge against the rear edge of said floor in arcuate continuation therewith, a pair of pivoted arcuate abutments for engaging the lateral edges of said screen, and a lever at the upper extremities of said abutments, said lever being below the arc of 65 said abutments and having a lower edge for pressing contact with the upper edge of said screen, the free edge of said lever being adapted to abut against the upper wall of said casing beneath the hinge of said door whereby the clos- 70 75 75

ing of said door will buckle said screen into intimate contact with said abutments.

2. In a hammer mill, a casing having a grinding chamber therein with a screen opening in its back wall, a screen for said opening, a frame hinged to the lower wall of said chamber and extending to the top wall thereof for engaging the screen, a lip hinged to the free end of said frame and having an eccentric heel part for engagement with the upper edge of the screen to compress the same into the frame, and a hinged cover mounted on the casing over said frame and adapted when closed to engage the upper end of the frame for binding the lip against the screen and holding the frame in place.

3. In a hammer mill, a casing having a grinding chamber therein, a hammer reel in the chamber of the casing, a screen disposed in the rear wall of the chamber within the casing, a screen holding frame in the casing extending from the bottom wall of the chamber and having its upper part terminating adjacent the top of the casing, said frame adapted to engage the marginal lateral edges of the screen to hold the same in place, a lip hinged eccentrically to the upper end of the frame and having a heel portion to engage the screen, a ledge carried by the casing beneath the top wall thereof to receive said lip, and a cover in the top wall of the casing adapted to be closed thereon and engage the upper end of the frame to clamp the same in place with the lip on said ledge and bind the heel of the lip against the upper edge of the screen and conform the latter to the frame.

35. 4. In a hammer mill, a casing having a grinding chamber therein, a hammer reel in the chamber of the casing, a screen disposed in the rear wall of the chamber within the casing, a screen holding frame in the casing extending from the

part terminating adjacent the top of the casing, said frame adapted to engage the marginal lateral edges of the screen to hold the same in place, a lip hinged eccentrically to the upper end of the frame and having a heel portion to engage the 5 screen and a cover in the top wall of the casing adapted to be closed thereon and engage the upper end of the frame to clamp the same in place and bind the heel of the lip against the upper edge of the screen and conform the latter to the 10 frame.

5. In a hammer mill, a main casing, a fan casing mounted on one side of the main casing, a horizontal shaft disposed axially in the main and fan casings, a hammer reel on the shaft in the 15 main casing, a fan on the shaft in the fan casing, an inlet extending downwardly in the front side of the casing at substantially a tangent to the bottom wall thereof beneath the hammer reel, an arcuate screen extending from the rear end of 20 the bottom wall in upright position in the rear side of the casing to receive therethrough ground material thrown off by the hammer reel for accumulation in the rear bottom portion of the casing, said casing having a collecting sump at its 25 lower rear portion the lower wall of which extends outwardly from the screen and generally horizontally relative to the bottom wall of the casing, and a substantially horizontally disposed conduit extending from said collecting sump at 30 said lower wall around the exterior of the main casing to said fan casing, whereby ground material tending to choke said conduit upon overloading of the main casing may gravitate along the bottom of the conduit without entirely closing the same so that the continuous draft of air 35 may gradually absorb the overload of ground material and prevent the choking of the mill.

CHARLES D. AMMON. 40
